UNITED STATES PATENT OFFICE.

FRANK E. HOBSON, OF BELLINGHAM, WASHINGTON.

FUEL-DISTILLING APPARATUS.

Application filed November 26, 1923. Serial No. 676,953.

My invention relates to improvements in fuel distilling apparatus and one of the objects of my improvements is to provide a retort in which the destructive distillation of 5 vegetable matter can be conducted and said material caused to pass through said retort under positive control whether said vegetable matter be sawdust or other comminuted wood waste, comminuted coal both coking 10 and non-coking, slack coal, also comminuted lignite, peat, oil shale and the like; another object of my improvements is to force said material through the retort without causing dust to pass therefrom into the gas-escape 15 conduits; another object of my improvements is to confine said material within an annular chamber in said retort and force the movement of said material through said chamber of the retort by the use of means 20 operative within the mass of the material and also on the inner walls of said chamber; another object of my improvements is to cause the movements within and on the interior walls of said material to occur either 25 alternately, simultaneously and in opposite directions, or alternately and in opposite directions with a period of pause between said consecutive movements; another object of my improvements is to cause the functioning 30 of the means used to produce said interior movements to also aid in passing heat through the mass of material; another object of my improvements is to provide for the easy escape of gas as soon as released 35 from said material and the saving of the entire quantity of said gas; another object of my improvements is to provide for the separate withdrawal of gas liberated during the drying and initial heating of said material 40 and the gas liberated during the subsequent stages of distillation; another object of my improvements is to prevent combustion within the retort with its accompanying loss of fuel and degrading of the released gases; 45 another object of my improvements is to provide an economical means of converting vegetable matter of low value into valuable products including high-grade fuel; and a further object of my improvements is 50 to provide distillation apparatus, for the purposes mentioned, simple and not expensive in design, easy to control, maintain and operate.

I attain these objects with the mechanism 55 illustrated in the accompanying sheet of drawings, which forms a part of this speci-

fication and in which Figure 1 is a front elevation of my retort in section on a medial, vertical plane, and Fig. 2 is a horizontal section of Fig. 1 on the line 2—2.

Similar indices refer to similar parts throughout. Certain parts are broken away for lack of space for the illustration or to show other parts hidden thereby.

More particularly: The inner shell 3 of the retort is cylindrical with a hopper-form bottom a^3 . Retort cylinder 3 has three enlargements near its upper end. The first of these from below is at 4, the second is at 6 and the third is the hopper-form top 8. Annular enlargement 4 is entered by the cylindrical outlet of enlargement 6, said outlet being of same diameter as the main part of shell 3 and is separate therefrom at its lower end to permit communication between the main body of the retort and said enlargement 4. Outlet 7 of hopper 8 is of the same diameter as the main body of 3 and enters enlargement 6 leaving space below its lower end for communication between the main body of the retort and said chamber 6. Said shell 3 and outlets 5 and 7 are in line and constitute portions of the shell of said retort. Material chute 9 leads from a source of material supply, not shown, to hopper 8. The bottom of retort 3 has flange 10 bearing on retort foundation 11. An outer wall 12 is cylindrical and concentric with retort shell 3, which it envelops with annular chamber a^{12} between. Wall 12 makes a closure of chamber a^{12} below by joining flange 10, and it is closed above by joining shell 3 beneath enlargement 4. An annular enlargement 13 of wall 12 is entered by pipe 15 from furnace 14 and serves to distribute the hot gases of combustion from said furnace around shell 3 that they may more freely enter chamber a^{12} . Damper 16 in pipe 15 controls the rate of flow of said hot gases into chamber a^{12} . Said hot gases find an exit from the top of chamber a^{12} through smoke pipe 17 leading to a stack not shown. Retort wall 12 is encased in nonconducting outer wall 18. A helical baffle 19 encircles shell 3 and compels gases from furnace 14 to encircle shell 3 several times before reaching outlet 17. Gas pipe 20 constitutes an outlet from chamber 4 into pipe 21 which latter also is an outlet for gas from chamber 6. Pipe 21 leads through an exhauster, not shown, to a condenser not shown. Beams 22 provide support for hop-

per 8. Gas pipe 23 is connected by a slip joint at a^{23} with the upper end of gas collector member a^{26} , and said slip joint is sealed with gland 34. Pipe 23 leads through 5 an exhauster to a condenser not shown. A louvered gas collector is suspended within retort 3 centrally and is composed of three sets of conical rings concentric with a common axis. The members of the lower set 10 24 of these conical rings may be more widely spaced than the others and each by preference has a cylindrical upper extension a^{24} . The middle set 25 of said conical rings may be most closely spaced and the 15 upper ring of this set is closed on top at a^{25} . The upper set 26 of said conical rings may be more widely spaced than said middle set and the upper ring thereof is closed at a^{26} around said pipe slip joint a^{23} . Each 20 of said three sets of conical rings is fastened to a single set of three vertical bars 27 which protrude beyond both ends of said sets of rings thus united and their upper ends are fastened to ring 28. To ring 28 are fastened 25 cables 29 which are fastened at the same place on lever 30 fulcrumed in pivot 31. The lower limits of the movement of said lever 30 around pivot 31 are controlled by stop screw a^{30} engaged in beam b^{30} . Pivot 30 31 is mounted in an arm of standard 40. A flaring pipe 33 leads from beneath the lower end of said louvered gas collector and passes through shells 3 and 12 and wall 18 to an exhauster and from thence to a condenser not shown. Pipe 33 is fastened to shell 3 by flanged ring a^{33} . On the upper end of pipe 33 is mounted slideway ring 32 on which the group of three bars 27 slide and for which it provides a guide. As 35 stated, 34 is a gland for the slip joint on the inner end of gas pipe 23. A plurality of heavy chains 35 depend from band 36 and hang vertically at spaced distances in the center of annular chamber b^3 between shell 40 3 and the louvered gas collector. Said chains reach nearly to the bottom of shell 3. Ring 36 is supported by three cables 37 fastened thereto and connected to a clevis pivoted to lever 38. Lever 38 is pivoted at 45 39 to the upper end of standard 40. Standard 40 is fastened to the top of post 41, which is fastened on and supported by hopper 8. Pipe 23 is clamped to post 41 at a^{41} . Lever 38 is free to turn on pivot 39 downward 50 till stopped by stop screw a^{38} which is engaged in beam b^{38} . In this way the lower limit of said lever movement is adjustable. Pulley 42 is mounted for revolution on shaft 43 which is fastened in bracket 44. In said pulley is crank pin a^{42} on which bar 45 is mounted. Cable 46 connects with one end of bar 45 at a^{45} and is reeved over lead block 47 which is mounted for revolution on shaft a^{47} and the latter is fastened in bracket 48. The other

end of cable 46 is connected to lever 30. Lead pulley 49 is mounted for revolution on shaft a^{49} which is fastened in bracket 50. One end of cable 51 is fastened to the other end of bar 45 at b^{45} and is reeved over pulleys 49 and 52 and then has its other end fastened to lever 38. Cables 46 and 51 are preferably not taut but provided with slack as shown near lever 30. This cable slack appears at lever 30 because this lever is bearing on stop a^{30} . When lever 38 is bearing on stop a^{38} said cable is taut at lever 30 and cable 51 is slack at lever 38. The purpose of this will be explained later. On pulley 42 is mounted power belt d^{42} driven by a source of power not shown. In a bearing fastened to foundation wall 11 is mounted a sprocket wheel 54 for revolution. Also in chain relation with said sprocket wheel 54 sprocket wheel 56 is 55 mounted for revolution on a bearing in a bracket also fastened to wall 11. On the shaft mounting sprocket wheel 54 is fastened power pulley 55 driven by belt a^{55} from a source of power not shown. A gang of endless chains 57 is mounted on sprocket wheels 54 and 56. These chains are adapted to pass over the bottom of hopper a^3 and drag the contents thereof out on to chute 58. The rate at which the material is removed by said conveyor chains will depend on the size and number of the chains used and their rate of movement. Chute 58 conducts the material to a receptacle not shown. 60 When pulley 42 is driven crank a^{42} causes bar 45 to move forth and back longitudinally through parallel positions. This causes cables 46 and 51 to reciprocate longitudinally and levers 30 and 38 are caused to oscillate thereby on their pivots. One lever moves upward as the other lever moves downward. Also, these movements are not simultaneous because sufficient slack is allowed in said cables to cause a period of 65 pause following each downward movement during which lever 30 bears on stop a^{30} and lever 38 bears on stop a^{38} . By preference the length of this pause is equal to the period of movement in order that gas collector 24, 25, 26, which is raised by lever 30 and falls by its own weight, will remain stationary while chains 35 move; and also in order that said chains, which are raised by lever 38 and fall by their own weight, will remain stationary while the gas collector moves. By preference, in practice I move the gas collector a short distance, only about one-half inch, and the chains about four inches. Because of the ratchet-like contour of the gas collector, with the inclined side of its teeth upward, when it moves downward most of the material in chamber b^3 moves downward with it, but its upward movement stirs and tumbles the material more than it carries it upward. Because of 70 75 80 85 90 95 100 105 110 115 120 125 130

the smooth contour of the links of chains 35 and their weight, their slow movements cause a stirring, loosening and tumbling of the material with little upward and more 5 downward movement of the same. This aids in the escape of gas from the material into the gas collector, prevents the formation of nodules of incrustations and moves the material downward as rapidly and only 10 as rapidly as it is removed, thus avoiding unduly packing the material in the bottom of the retort.

Because of the positive downward movement of all the material in chamber b^3 the 15 rate of removal of the carbon residue by conveyor 57 controls the movement of the material through the retort. In practice, sawdust, which heretofore has presented insuperable difficulties in destructive-distillation retorts, is treated without difficulty in 20 my apparatus and changed from fuel of low value to valuable byproducts and high-grade fuel. Because of the described slow, recurrent and moderate movements within the 25 material impelled in my apparatus no considerable quantity of dust enters the gas conduits. This is a serious difficulty in other retorts but, in practice, I have had no trouble from it. For these reasons my apparatus 30 is well adapted for continuous operation on a commercial scale even when distilling sawdust and similar wood waste.

As the material moves downward in chamber b^3 under the recurrent urgings of chains 35 and gas collector it packs more closely and on reaching hopper a^3 it is well able to seal the openings, through which conveyor 57 operates against the entry of air. By the 40 time the material reaches the lowest ring of the gas collector it is relieved of its volatile content the last of which can enter the collector at this point. In the upper part of chamber b^3 the material is more loosely associated. For this reason external gas collectors 4 and 6 are used in connection with the interior gas collector in order to afford 45 an easier escape for the gas liberated here into these collectors than the path through the material above and out of hopper 8 where it would be lost. The most volatile gas recovered enters the louvered collector between wider-separated rings 26, and also enters external collectors 4 and 6. The partition a^{25} separates the chamber in the 50 louvered gas collector into a lower and upper part. Thus this most volatile gas is carried off in conduits 21 and 23. Excepting to this extent, no attempt is made within the retort to separate the gaseous emanations or distilled by-products from the material into grades. The greater part of the 55 gas liberated enters the gas collector between middle rings 25. At this part of the retort the heat is sufficient to begin the carbonization of wood products and also raise the

temperature of peat, slack coal, and the like, to temperatures which liberate their volatile content rapidly. Thus by the time the material has reached the upper ring 24 it is free of the bulk of its volatile content and 60 in danger of being made too hot for the remaining volatile content by the furnace gases which first contact with the retort here. For this reason I prefer to space rings 24 more widely than the others. Then 65 to insure against the entry of solid material within the gas collector chamber, collars a^{24} are added to the more widely-spaced rings 24. All gas entering the collector below partition a^{25} is, without difficulty, drawn 70 off through pipe 33. To do this, in practice, an exhauster is not always used, although a low vacuum is found useful.

In practice, I have found my retort with reciprocating chains and louvered gas collector effective in distilling wood waste, 75 peat, lignite, and slack from both anthracite and bituminous coals whether coking or non-coking. Usually the solid residue from these materials is of more fuel value than was the 80 whole material before passing through the retort; and the byproducts recovered are usually of much greater value than the 85 solids.

Having thus disclosed my invention, what 90 I claim as new and desire to secure by Letters Patent is,—

1. In a destructive-distillation retort in combination, a vertical retort shell, means adapted to heat said retort shell, a louvered gas collector flexibly suspended centrally in 95 said retort shell, means adapted to shift said gas collector vertically whereby material in the retort chamber between said gas collector and said retort shell is caused to move downward in intermittent stages during distillation by the vertical shifting of said gas collector and the volatile content of said material is liberated by heat from said heated retort shell and passes into said gas collector, and draw-off means for the volatiles in said gas collector. 100

2. In a destructive-distillation retort in combination, a vertical retort shell, means adapted to heat said retort shell, a louvered gas collector flexibly suspended vertically and centrally in said retort shell, means for shifting said gas collector vertically, means adapted to conduct material for distillation 105 into the top of the chamber between said gas collector and said retort shell, means adapted to withdraw said material continuously from the bottom of said retort shell, and means adapted to withdraw gas as it collects in said gas collector, the material fed in at the top being caused to move downward through said retort between said retort shell and said gas collector by said shifting movement thereof in intermittent stages during distillation is heated as it moves, volatile 110

emanations therefrom are caught by said gas collector and withdrawn therefrom and the carbonized material is withdrawn from the bottom of said retort.

5 3. In a destructive-distillation retort in combination, a vertical retort shell, means adapted to heat said retort shell, a louvered gas collector suspended centrally and vertically in said shell, metal chains suspended 10 vertically in the chamber between said gas collector and said retort shell, means adapted to shift said chains vertically in said chamber, and draw-off means for the gas from said gas collector as it accumulates therein, the 15 material in said retort chamber being caused to move downward therein during distillation by said shifting chains, the volatile content thereof being liberated by heat from said shell passes into said gas collector from 20 which it is removed through the draw-off means.

4. In a destructive-distillation retort in combination, a vertical retort shell, means adapted to heat said shell, a vertically shiftable louvered gas collector flexibly suspended centrally and vertically in said shell, a plurality of chains suspended vertically at spaced distances in said retort between said gas collector and said shell, means adapted 25 to elevate said chains and said gas collector alternately vertically, draw-off means for the gas from said gas collector as it accumulates therein, means adapted to conduct material adapted for distillation into the top of the 30 chamber between said retort shell and said gas collector, and means adapted to withdraw said material continuously from the bottom of said chamber, the said material being caused to move downward through 35 said chamber during distillation by the shifting movements of said chains and said gas collector, the gaseous emanations liberated therefrom by said heat from said retort shell passing into said gas collector and being 40 withdrawn therefrom and the carbonized material being continuously withdrawn from the lower part of said retort.

5. In a destructive-distillation retort in combination, a vertical retort shell, means 45 adapted to heat said retort shell, a louvered gas collector adapted for vertical shifting movement consisting of superposed and spaced conical rings vertically joined together and flexibly suspended centrally in 50 guides in said retort, a plurality of spaced chains suspended vertically in the retort chamber between said retort shell and louvered gas collector, means adapted to shift vertically said gas collector and said chains

in said retort chamber, means adapted to 60 conduct material into the top of said retort chamber and withdraw it from the bottom thereof continuously, and means to conduct gas from said gas collector as it accumulates 65 therein, the material, forced through said retort, being distilled therein and the gas emanating therefrom being collected and removed and the solid residue is withdrawn from the bottom thereof.

6. In a destructive-distillation retort in 70 combination, a vertical retort shell having annular gas collectors on its periphery, means adapted to heat said retort shell, a louvered gas collector suspended centrally in 75 said retort shell, a plurality of spaced chains suspended vertically in the annular chamber between said louvered gas collector and said retort shell, means adapted to vertically shift said louvered gas collector and said chains, means adapted to conduct material 80 into the top of said retort chamber and withdraw it from the bottom thereof continuously, and means to conduct gas from said gas collectors as it accumulates 85 therein, the material while being passed through said retort, being distilled therein, the gaseous emanation therefrom withdrawn from the retort and the residue solids withdrawn from the retort.

7. Destructive distillation apparatus comprising an annular retort chamber between a stationary cylindrical vertical wall and an inner concentric louvered gas collector flexibly suspended and vertically shiftable in 90 vertical guides, means to conduct material suitable for distillation into the top of said chamber, means to withdraw continuously the solid residue from the bottom of said chamber, means to vertically shift said suspended gas collector, means to conduct gas 95 from said gas collector during shifting movements and means to heat said stationary wall.

8. In a destructive-distillation retort in 100 combination, a retort shell, a louvered gas collector suspended centrally and vertically mounted for vertical movements in said shell, a plurality of spaced chains suspended 105 vertically in the retort chamber between said gas collector and said shell, means adapted to cause said gas collector and said chains to shift vertically alternately with a period of pause after a cycle of shifting movement of each, and means adapted to separately vary the length of said shifting movements and the length of said periods of pause.

FRANK E. HOBSON.
